Inventor:

John P. Lynn.

By *Murphy & Murphy* Attest:

UNITED STATES PATENT OFFICE.

JOHN P. LYNN, OF CHICAGO, ILLINOIS, ASSIGNOR TO DUR-O-LITE PENCIL COMPANY, OF CHICAGO, ILLINOIS, A CORPORATION OF ILLINOIS.

PENCIL.

Application filed June 16, 1927. Serial No. 199,238.

This invention relates to a pencil of the type which utilizes mechanical means for advancing a lead, as required, into writing position. The present improvements are directed to the construction of a pencil body in which is contained an active lead and also, if desired, other reserve leads, as well as the propelling means therefor.

The pencil body with which this invention is concerned is formed of material which can be moulded to the desired size and shape. For this purpose it is common to employ heat and pressure. The resulting product may be of rather brittle character, or it may be slightly warped or bent from the true form of the mould in which it was produced. Such deficiencies are difficult to overcome, and tend greatly to impair the usefulness of the pencil.

The present invention is designed to provide for the production of a body which is suitably reinforced. By the provision of such reinforcement, strength is added to the structure so that it will withstand hard usage without breaking. In addition, the form given to the body by the mould in which it is produced will be accurate and true so as to function perfectly with the associated propelling mechanism.

With objects and purposes such as have just been outlined, the present invention is largely concerned. For a suggestive embodiment of my invention, reference may be had to the accompanying drawing wherein:

Figure 1 is a view partly in side elevation and partly in longitudinal section of a pencil body equipped with a propelling mechanism;

Fig. 2 is an enlarged detail in section of the lower end of the pencil body with a portion of the propelling mechanism, shown most in elevation, applied thereto; and

Fig. 3 is a transverse section taken on line 3—3 of Fig. 1.

The pencil herein illustrated by way of example comprises a body A having, if desired, at its upper end a ferrule 5, in which is held an eraser 6. Fitted to the lower pencil end is a cone-shaped tip B having a rotatable connection therewith.

The pencil body is shown as provided with an axial opening 7 having one or more slots therein for the accommodation of a head 8 which is carried on a threaded plunger 9.

At its lower end the passage 7 opens into a round chamber 10 of enlarged diameter wherein is also received a tube 11 extending upwardly from the tip B. The walls of this tube are frictionally engaged with the body walls surrounding the chamber 10 so as to establish a rotatable connection between the tip and pencil body. Extending axially within the tip is a guide tube 12 wherein is slidably received an active lead 13. At its upper end the guide tube is supported by the convergence of the tube walls 11 which are internally threaded to co-operate with the threads of the plunger whereby to advance the same when the tip is rotated relative to the pencil body.

The construction thus far described suggests one advantageous form of pencil propelling mechanism. The body of the pencil, according to this invention, may be formed by the application of pressure and heat to a suitable material which is capable of being moulded to the required shape. It is the purpose of this invention to reinforce such a body, and as a suggestive means for this purpose I have shown a wire 14 in the form of a continuous spiral which is extended lengthwise of the pencil body for a desired portion of its length. This wire is embedded within the material forming the body so as to lie interiorly thereof. Where the body walls are of reduced thickness to form the enlarged chamber 10 of the lower end thereof, the coils of its wire may be tangential to the walls of this chamber, as shown in Fig. 1, or may be slightly exposed within the chamber, as suggested in Fig. 2. In the latter case, the walls of the tube 11 engage directly with the spiral when the tip is fitted to the pencil body, thus establishing a metal to metal contact. The use of a wire coil for this reinforcement is desirable, inasmuch as the material forming the body may flow freely therethrough, when being moulded to shape. It is possible, however, to obtain satisfactory results by a reinforcing medium otherwise formed, as, for example, by the use of one or more rings arranged in spaced relation, or by providing one or more bands or sleeves extending lengthwise of the pencil. In any such construction, the necessary reinforcement is provided, the reinforcing medium is wholly concealed, and, if desired, a small portion of the reinforcing means may

be exposed within the lower chamber for contact with the upstanding tube of the tip.

I claim:

1. In a pencil, a moulding forming a body in which is an axial opening, and a reinforcement within the body extending longitudinally thereof and exposed in part upon the walls surrounding said opening whereby to engage with a tip when fitted thereto, substantially as described.
- 5
- 10

2. In a pencil, the combination of a moulding forming a body in which is an axial opening, and a reinforcement extended spirally within the body for a substantial portion of its length and exposed in part upon the walls surrounding said opening whereby to engage with a tip when fitted thereto, substantially as described.

JOHN P. LYNN.
